UNITED STATES PATENT OFFICE.

JAMES K. ROSS, OF SPRINGFIELD, OHIO.

LETTER-BOX BELL.

SPECIFICATION forming part of Letters Patent No. 269,961, dated January 2, 1883.

Application filed March 20, 1882. (No model.)

To all whom it may concern:

Be it known that I, JAMES K. ROSS, of the city of Springfield, in Clarke county, and State of Ohio, have invented certain new and useful 5 Improvements in Door-Bells, Letter-Ports, &c., of which the following is a specification.

My invention has for its object the provision of means, all located compactly together and on the same side of the door or partition, 10 whereby the same action that rings the door-bell shall uncover a port or chute, through which letters may be dropped into any desired receptacle, and whereby the said port or chute shall, when all strain upon the bell-pull is removed, 15 be automatically recovered.

My invention has for its further object the connection with or application to the combined device aforementioned of a suitable door-plate, as hereinafter described.

20 My invention, when embodied in suitable material, whether with or without the door-plate, constitutes a new, elegant, cheap, and serviceable article of manufacture, which can be kept and sold as an entirety, and can be applied and put in use by any one, no matter how unskilled in mechanics he may be.

In the accompanying drawings, forming a 25 part of this specification, and to which drawings reference is hereby made, Figure 1 represents a front elevation of a device illustrating my invention. Fig. 2 is a transverse sectional view of the device shown in Fig. 1, and taken at the dotted line X X, and looking toward that side of the device which is on the left hand in Fig. 1. Fig. 3 is an elevation of a 30 portion of my device, looking at it from the rear. Fig. 4 is a detached sectional elevation of one portion of my device. That form of mechanism for ringing the bell which is shown 35 in said figures is of my invention.

A indicates the exterior shell or frame-work of the entire device. This frame-work preferably consists of a front piece, B, and side pieces, C C, one of said side pieces being suitably secured to said front piece at or near each end or edge of the latter. These side pieces are connected to the door or other partition by bolts or screws or rivets, preferably as shown by the bolts a, whose ends pass through and 40 beyond the door or partition, and upon each of which ends a nut is respectively screwed.

This frame-work may be and is preferably of an ornamental design, and the details of length, width, and shape may be varied to suit the design of the door or partition or building to 55 which the whole device is applied, or the taste of the person interested in its manufacture, sale, or application. Thus, for example, the lower flutings, b and d, of the plate B, and the corresponding bottom parts of the side pieces, 60 C, may be dispensed with.

In the frame-work is the open space D, and this space is, when the device is not operated on to ring the door-bell or to use the letter-box, covered by a suitable plate, as E. In the 65 present instance the plate is arched, as shown.

70 Preferably located inside of the frame-work are the levers or oscillating supports H, one of which is at or near one side of the frame-work and the other at or near the other side of the frame-work. Each lever H is preferably connected to its adjacent side piece C, and in the following manner: The inner surface of the side piece C is provided with a ring, e, (see Fig. 4,) projecting from said surface, and 75 transversely slotted through at h, forming a chamber, g, and is further provided with a hub or boss, f, of much smaller diameter than the inside diameter of said ring, the said boss being located within and concentric with the 80 ring. The other side piece C is provided with a similar ring e and boss f, and located in a similar manner on said second side-piece.

The lever H is provided with a ring, l, into 85 which the boss f of piece C enters and forms the journal-bearing upon which the lever turns. A rivet or bolt through the center of the boss and ring l and the lever H prevents the latter from leaving its position on the side piece and the ring from slipping off the hub or boss f. 90 The lever H has a chamber, g, whose annular edge h' fits closely against the ring e. Around the boss f and within the chamber g a circular spring, j, is placed, one end of which is fastened in the slot h, and the other end is passed 95 through a slot in the edge of ring l, and made fast thereto. The spring is so strained that it tends to keep the upper end of the lever against or near the rear part of the box, and near the door or partition. The top of this 100 lever is preferably provided with a carrying-flange, m, to which latter the plate or cover E

is secured. This lever has an arm, I, employed to operate the mechanism for ringing the bell. In the present instance a lever, K, having two arms, *p r*, is pivoted at the junction of its two arms to a support, *n*, fixed to the frame-work A, preferably as shown. A stiff piece, L, connects the free end of arm I and the free end of arm *p*, being hooked or pivoted to the arm I and sliding in the arm *p*. A head, *q*, on the free end of the piece L prevents the latter from sliding out of the arm *p*. A spiral spring, M, arranged around the piece L, and compressed between the end of arm I and arm *p*, tends to keep the arm *p* in close juxtaposition with head *q*. The free end of the arm *r* carries a stiff coiled spring, S, which latter carries the hammer T, arranged to strike against the bell or gong U, the latter being attached to the frame-work, preferably as shown.

20 The cover E is provided with some suitable projection or handle, as W, and also with a chute-board, as Y.

The mode in which my invention operates is as follows: When it is desired to ring the door-bell the operator takes hold of the handle W and draws back the cover E, thus moving the levers H and overcoming the resistance of the springs *j*. As the levers H are moved the lever I is moved, and spring *m* is compressed and actuates arm *p*, which, moving arm *r*, throws hammer T against the bell and rings the latter. When the cover has been fully drawn back the letter-chute is exposed, and opportunity is afforded to drop any papers, letters, or other communications through the letter-port, the letters, &c., sliding through the letter-port on the chute-board. When the operator relinquishes his hold upon the handle W the springs *j*, being free to act, force the levers back to their first position, thereby closing the letter-port, and at the same time, through the agency of the arms I and *r* and spring and hammer, again ringing the bell.

When preferred the bell and a part of all of its immediate adjuncts may be placed elsewhere than within the frame-work, in which event the bell-wire will be operated through the agency of the lever H, and preferably by means of its arm I.

50 The space on the frame-work, or on the door or partition immediately above the cover E, may be employed as a door-plate. When the latter space is employed the door-plate usually consists of a frame, as Z, preferably an extension of the frame-work A, and formed with or united to the latter. This frame Z may contain a regular brass plate, on which the name of the owner is to be cut or otherwise inscribed; but for the purposes of the general sale of the 60 device I prefer to leave a space in the frame, in which a card or other substance bearing a suitable name or inscription may be placed, the whole being covered with glass.

One principal feature of my invention consists in the frame-work carrying the letter-chute cover containing the mechanism for automatically returning the cover over the let-

ter-chute and ringing the bell, being within the said frame-work or compactly connected to and forming an integral and constituent part of 70 same.

Those features which relate to the springs for actuating the levers, and the precise location of the same, and the mechanism for ringing the gong, may be varied at will without 75 altering the principal features of my invention.

The handle of the cover E may be lettered with the word "Bell," and where the name or number of a person or residence is not desired upon the middle face, *t*, of the frame-work the word "Letters" may be placed thereon. The side pieces preferably carry near their bottom hooks or slotted studs N, to the better enable the pieces and frame-work to be bolted or riveted to the door or other partition.

80 The cover E may, if desired, be placed at a lower point in the frame-work, and the parts within altered to conform with this change of location.

What I claim as new and of my invention, 90 and desire to secure by Letters Patent, is—

1. As a new article of manufacture, the frame-work or box A, in combination with the cover E, and mechanism for automatically causing the cover to close the letter-port, and for causing the movement of the cover E to ring the bell, all of said mechanism being contained within said box, the latter, together with its contents and the cover E, being located on one side of the door or partition, substantially as 95 100 and for the purposes specified.

2. The frame-work A, and cover E, and chute-board Y, and the levers H, actuated by mechanism for causing them to return cover E over the port-chute and to ring the bell, substantially as and for the purposes specified.

3. The combination of cover E, side pieces, C, provided with boss *f*, and chamber *g*, and slot *h*, and the lever H, provided with hub-ring *l*, and ring *e*, and slot *h*², and spring *j*, located within said chamber, substantially as and for the purposes specified.

4. The combination of cover E, frame-work A, levers H, and a suitable spring for retracting the levers, and the stud *n*, arms *p r*, connecting-piece L, spring M, and hammer and bell, substantially as and for the purposes specified.

5. The frame A and cover E, constituting a box for containing the door-bell, and mechanism for causing it to be rung when the cover is opened, said box being provided with a door-plate extension, Z, all located on one side of the door, substantially as and for the purposes specified.

6. The combination of the cover E, provided with handle W and board Y, and frame-work A, and mechanism for automatically retracting the cover and for ringing the bell, substantially as and for the purposes specified.

JAMES K. ROSS.
